UNITED STATES PATENT OFFICE.

ROBERT NOAH GRINER, OF KOKOMO, INDIANA.

POURING VESSEL.

1,344,688.

Specification of Letters Patent. Patented June 29, 1920.

Application filed December 27, 1919. Serial No. 347,706.

To all whom it may concern:

Be it known that I, ROBERT NOAH GRINER, a citizen of the United States, residing at Kokomo, in the county of Howard and State 5 of Indiana, have invented a new and useful Pouring Vessel, of which the following is a specification.

This invention relates to new and useful improvements in metal founders' ladles, and 10 it is the primary object of the invention to provide a device of this character wherein the molten metal will be taken from the bottom of the ladle, and discharged from the spout, located adjacent the upper edge 15 thereof.

A further object of the invention is to provide a device of this character having a channel-way formed in the refractory lining thereof, the channel-way being formed in 20 the bottom of the ladle to insure against the slag passing through the spout of the ladle when the metal is being poured therefrom.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawing:—

Figure 1 illustrates a longitudinal sectional view through a ladle constructed in 35 accordance with the present invention; and

Fig. 2 illustrates a top plan view of the same.

Referring to the drawing in detail, the 40 device is shown as including a metallic body portion 5, which is preferably circular in cross section, and having the forward and rear portions thereof offset as at 6, to provide spouts for directing the metal from the 45 ladle.

A relatively thick lining 7 of a refractory material forms a part of the ladle, the same being formed into an enlargement 8 formed adjacent one of the spouts 6, the enlargement 50 9 having a relatively straight wall for dividing the interior of the ladle into a containing compartment and a pouring compartment, the pouring compartment being indicated at 10 and has its forward wall

inclined as at 11 to conform to the contour 55 of the spout 6, to which the lining is secured.

Disposed in the bottom of the lining 7 and arranged intermediate the width thereof, is a channel-way 12, which extends from 60 a point in close proximity to the rear inner wall of the ladle, under the straight wall 9 of the enlargement, where the same has communication with the pouring compartment 10. 65

From the foregoing it is obvious that when molten metal is poured from the ladle, the clear metal passes through the passage-way 12, from the containing compartment, to the pouring compartment 10, the metal 70 finding its way from the ladle over the spout 11.

Due to the fact that the straight wall 9 of the enlargement terminates at a point in 75 the same plane with the bottom of the containing compartment, no metal may pass into the pouring compartment 10 unless the same passes through the channel-way 12. The operator, in using a ladle as constructed 80 in accordance with the present invention, 85 watches the quantity of metal within the ladle and when the slag, which forms on the top of the metal, reaches the bottom of the ladle the ladle is moved to an upright position, and the slag poured from the spout 85 formed at the rear of the ladle, the passage-way 12 eliminating any possibility of the slag passing into the chamber 10.

Having thus described the invention, 90 what I claim as new is:—

1. A metal founder's ladle including a metallic body portion, a lining of refractory material positioned within the body portion, said lining having an enlargement forming a part thereof, a relatively straight wall 95 forming a part of the enlargement, said relatively straight wall dividing the interior of the ladle into a retaining compartment and a pouring compartment, said lining having a channel-way formed in the 100 bottom thereof, said channel-way being in communication with the pouring chamber, and said straight wall of the enlargement terminating in the same plane as the upper surface of the bottom. 105

2. A metal founder's ladle including a metallic body portion having offset portions providing spouts, a lining of refrac-

2
tory material provided in the body portion, an enlargement forming a part of the lining and having a relatively straight wall dividing the interior of the ladle into a retaining chamber and a pouring chamber, the upper wall of said pouring chamber conforming to the offset portion of the ladle, and said retaining chamber having means to provide communication between the retaining chamber and pouring chamber, said

means being disposed below the upper surface of the bottom of the ladle.

In testimony that I claim the foregoing as my own, I have hereto affixed my signature in the presence of two witnesses.

ROBERT NOAH ^{his} X GRINER.
